UNITED STATES PATENT OFFICE.

WALTER W. GREEN, OF WING, ILLINOIS.

GRAIN-CAR DOOR.

1,176,958.

Specification of Letters Patent. Patented Mar. 28, 1916.

Application filed March 4, 1915. Serial No. 12,044.

To all whom it may concern:

Be it known that I, WALTER W. GREEN, a citizen of the United States, residing at Wing, in the county of Livingston and State of Illinois, have invented a new and useful 5 Grain-Car Door, of which the following is a specification.

The device forming the subject matter of this application is a grain car door, and the 10 invention aims primarily, to provide a flexible door of novel form, adapted for use on a grain car.

In addition to improving the specific construction of the door, the invention aims to 15 provide novel means for actuating the door, for supporting the door while the same is being raised and lowered, and to provide a novel form of auxiliary door constituting a part of the door proper.

20 It is within the scope of the disclosure to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed, without departing from the spirit of the invention.

35 In the accompanying drawings: Figure 1 shows the invention in front elevation; Fig. 2 is a section on the line 2—2 of Fig. 1; Fig. 3 is a section on the line 3—3 of Fig. 2; Fig. 4 is a fragmental vertical section showing a 40 portion of the door; Fig. 5 is a fragmental elevation showing a portion of the actuating mechanism whereby the door is operated and controlled; Fig. 6 is a detail of the hinge union whereby the auxiliary door is 45 operatively connected with the main door; Fig. 7 is a fragmental end elevation of the door actuating means.

In carrying out the present invention there is provided a supporting structure 50 which may be in the form of a grain car, one wall of which is denoted by the numeral 1, the wall 1 being provided with a doorway 2. One of the longitudinal roof beams of the car is shown at 3 and another of the longi- 55 tudinal beams appears at 4.

Depending bearings 5 are secured to the beam 3 and in the bearings 5 is journaled for rotation an actuating shaft 6 provided with a ratchet wheel 7 engaged by a back stop pawl 8 pivotally carried by a support 9 60 attached to the beam 3, as clearly disclosed in Fig. 5. Secured to the shaft 6 is a ratchet wheel 10. Mounted to swing on the shaft 6 is a U-shaped yoke 11 inclosing the ratchet wheel 10, the lower portion of the yoke 11 65 being contracted to form arms 12 supporting a pivot element 14 on which is mounted to swing a lever 15 provided at its upper end with an integrally formed pawl 16 which coacts with the ratchet wheel 10 to 70 actuate the same and the shaft 6.

The door proper which controls the doorway 2 is a flexible structure and is made up of a plurality of transverse panels 17 preferably fashioned from metal. The lower edge 75 of any panel 17, considered as an upper panel, is bent upon itself as shown at 18 to form a hook-shaped socket 19 in which the upper edge of the next lower panel is loosely received. Mounted on the panels 17 are 80 hinge elements 20 which are offset as shown at 21 to clear the sockets 19. The offset portions 21 of the hinge elements 20 are united by pivot elements 22. The constituent slats or panels 17 of the door may be reinforced 85 upon their inner faces by longitudinal battens 23. Chains 34 or other flexible elements are provided, the upper ends of the chains 34 being wound around the actuating shaft 6, the chains being extended downwardly along the front of the flexible door, and the lower ends of the chains being secured to the lowermost panel 17 of the door. 90

Mounted upon the roof beams 4 or otherwise supported are lateral open tracks 24, 95 preferably in the form of channels, the forward ends of the tracks 24 being downwardly curved as clearly shown at 25. When the lowermost panel 17 of the flexible door rests upon the floor 26 of the car, the uppermost panel of the flexible door lies in the curved, downwardly extended ends 25 of the tracks. 100

In one of the panels 17 adjacent the lower end of the flexible door there is interposed 105 an auxiliary door 27, the lower edge of which is bent as shown at 28 to form a hook-shaped socket 29 engaged with the upper edge of the lowermost panel of the main door. Hinge elements 31 coöperate with 110

the auxiliary door 27 and hinge elements 30 coöperate with one of the panels 17 of the main flexible door. The hinge elements 30 and 31 are provided with upright slots 32 receiving slidably, securing elements 33 mounted respectively in the auxiliary door 27 and in that slat 17 of the main door to which the hinge elements 30 are applied.

In practical operation, the shaft 6 is rotated by means of the ratchet wheel 7, the lever 15 and the pawl 16, the lever 15 tilting on the pivot element 14 and the yoke 12 swinging on the shaft 6. The chains 34 thus are reeled onto the shaft 6 and the main door, comprising the panels 17 is elevated, the door moving upwardly and rearwardly into the tracks 24. The door is prevented from dropping downwardly, due to the engagement between the back stop pawl 8 and the ratchet wheel 7 on the shaft 6. As the main, flexible door traverses the curved portions 25 of the tracks 24, the upper edges of the panels 17 move sufficiently in the curved sockets 19 so that the door may have the necessary flexibility and transverse movement between its parts to enable the door to coöperate with the tracks 24, the function of the hinges 20—21—22 being obvious.

When it is desired to open the auxiliary door 27, the same is lifted until its socket 29 no longer is engaged with the upper edge of the lowermost panel 17 of the main door. Thereupon the auxiliary door 27 may be swung to an open position on its hinges 30—31. The hinge elements 30—31 are slotted as shown at 32 for two reasons. First, in order that the auxiliary door may be lifted as before said, to disengage its socket 29 from the upper edge of the corresponding panel of the main door; and secondly, in order that the flexibility of the main door, as the same traverses the curved ends 25 of the tracks 24 may not be interfered with by the presence of the hinge elements 30—31.

Having thus described the invention, what is claimed is:—

1. In a device of the class described, a flexible door comprising upper and lower panels, the lower edge of the upper panel being bent upon itself to form a U-shaped socket which projects beyond one vertical face of the upper panel, the upper edge of the lower panel being loosely received in the socket; a hinge element secured to the upper panel above the socket; a hinge element secured to the lower panel below the socket; and a pintle uniting the hinge elements; the hinge elements being offset adjacent the pintle to clear the socket, and the pintle being located in a common horizontal plane

to the upper edge of the lower panel; and car carried means for guiding the door.

2. In a device of the class described, a flexible door comprising a group of panels; means for pivotally connecting the panels with each other; an auxiliary door interposed in one of said panels and detachably united at its lower edge by a lip and socket connection with another of said panels; a hinge connected with the auxiliary door; and means for connecting the hinge with one panel of the group for movement transversely of the pintle of the hinge, to permit a release of the lip and socket connection and to permit a swinging of the door.

3. In a device of the class described, a flexible door embodying panels; means for pivotally connecting the panels; one of the panels having an opening; coöperating members including another of the door panels, and an auxiliary door for the opening, the auxiliary door and a third one of the panels being detachably united by a lip and socket connection; a hinge; means for securing the hinge to one of said coöperating members; and means for securing the hinge to the other of said coöperating members for movement transversely of the pintle of the hinge, to permit a release of the lip and socket connection and to permit a swinging of the auxiliary door.

4. In a device of the class described, a door comprising a group of hingedly connected panels; a car with which the door co-operates and an auxiliary door interposed in one of the panels, the auxiliary door comprising a socket receiving the longitudinal edge of another of said panels; and means for connecting the auxiliary door with a third panel of the group for pivotal movement and for movement parallel to the socket-engaged panel to permit a disengagement of the socket from the socket engaged panel.

5. In a device of the class described, a flexible door comprising panels; an auxiliary door including a socket receiving one edge of one panel; and means for connecting the auxiliary door with the flexible door for swinging movement, and for movement parallel to the plane defined by the flexible door thereby to permit a disengagement of the socket from said panel.

In testimony that I claim the foregoing as my own, I have hereto affixed my signature in the presence of two witnesses.

WALTER W. GREEN.
